UNITED STATES PATENT OFFICE.

WILLIAM IRMSCHER, OF BROOKLYN, NEW YORK.

TABLE IMPLEMENT.

SPECIFICATION forming part of Letters Patent No. 593,223, dated November 9, 1897.

Application filed February 21, 1896. Serial No. 580,190. (No model.)

To all whom it may concern:

Be it known that I, WILLIAM IRMSCHER, a citizen of the United States, and a resident of Brooklyn, in the county of Kings and State 5 of New York, have invented certain new and useful Improvements in Table Implements, of which the following is a specification, reference being had to the accompanying drawings, forming a part thereof, in which similar 10 letters of reference indicate corresponding parts.

This invention relates to table implements; and the object thereof is to provide a device of this class which is simple in construction 15 and operation and also comparatively inexpensive, a further object being to provide a corn-holder or device by means of which an ear of hot corn may be manipulated without applying the hands thereto and also a support 20 for said device when in use.

The invention is fully disclosed in the following specification, of which the accompanying drawings form a part, in which—

Figure 1 is a side view of a corn-holder and 25 my improved support, and Fig. 2 an end view of the support.

In the practice of my invention I provide a corn-holder which consists of two separate similar parts, each of which is adapted to be 30 connected with one end of an ear of corn and each of which comprises a handle A, to which is secured a fork B, which is adapted to be inserted into the end of an ear of corn, and the fork B is composed of a strong stiff wire, 35 the middle portion of which is bent to form a shank b, which is secured to the handle in any desired manner; but my invention is not limited to this construction, and the fork B and handle A may be of any desired form. 40 I also provide a support which is composed of wire bent into the form shown in Figs. 1 and 2. In this operation two separate pieces of wire are preferably employed, each of which is bent to form an end piece which 45 comprises two standards D and D², which are united at the top by a cross-piece d, which is bent to form a depending yoke or loop, and one end of the wire is bent to form a foot d², and the other end is bent upwardly, as shown 50 at d³, and projected horizontally, as shown at d⁴, and each of the ends d⁴ is formed into a

ring or loop d⁵, which is adapted to inclose the other horizontal portion d⁴, as clearly shown in Fig. 1. As thus constructed the ends are adjustable longitudinally and are 55 adapted to be brought nearer together or separated, as will be readily understood, and the support is also by this means adapted for use in connection with ears of corn of different lengths. 60

The operation will be readily understood from the foregoing description when taken in connection with the accompanying drawings.

The corn fork or forks A are connected with the ear of corn, as shown in Fig. 1, and the 65 shanks of the handles are placed in the loops or yokes d of the support, and by means of this arrangement the said ear of corn is supported without coming in contact with the table or the cloth thereon and said ear of 70 corn may be manipulated without applying the hands thereto.

This device is simple in construction and operation and comparatively inexpensive, and it is evident that changes in and modifications of the construction herein described 75 may be made without departing from the spirit of my invention or sacrificing the advantages thereof.

Having fully described my invention, I 80 claim as new and desire to secure by Letters Patent—

As a new article of manufacture a table implement consisting of two end pieces each having two standards, a depending loop or 85 cross-piece engaging the said standards at their upper ends, a foot secured to one of said standards and integral therewith, an upwardly, then horizontally directed projection secured to the other of said standards and a 90 hook formed on the end of said projection or horizontal portion and adapted to respectively engage one with the other, all of said parts being combined substantially as described.

In testimony that I claim the foregoing as 95 my invention I have signed my name, in presence of the subscribing witnesses, this 20th day of February, 1896.

WILLIAM IRMSCHER.
